UNITED STATES PATENT OFFICE.

OTTO HAENTJENS, OF HAZLETON, PENNSYLVANIA.

PUMP SYSTEM.

Application filed March 6, 1923. Serial No. 623,211.

To all whom it may concern:

Be it known that I, Otto HAENTJENS, a citizen of the German Republic, residing at Hazleton, in the county of Luzerne and State of Pennsylvania, have invented certain new and useful Improvements in Pump Systems, of which the following is a specification.

My invention relates to pump systems, and particularly to pump systems of the general type illustrated in my copending application Ser. No. 532,784, filed January 30, 1922, upon which Patent No. 1,445,507, dated February 13, 1923, has been granted me for the priming of centrifugal pumps. The object of my present invention is to provide an improved check valve arrangement in the priming connection between the centrifugal pump and the priming pump, and particularly to provide a valve which is positively opened during the drive of the priming pump, but is closed by the pressure of the discharge from the centrifugal pump when the latter is started during the temporarily continued run of the priming pump.

In the accompanying drawings—

Fig. 1 is a vertical section through a check valve and associated parts, the valve being shown mounted directly on the casing of a centrifugal pump, while the associated priming pump and its motor are merely diagrammatically shown;

Figs. 2 and 3 are respectively sections on the lines 2—2 and 3—3, Fig. 1.

In a system of the present type, the centrifugal pump 5 is primed by an auxiliary pump P such as illustrated in my copending application Ser. No. 532,783, filed January 30, 1922. The present valve is arranged in the priming suction line S, and preferably adjacent the centrifugal pump and serves to prevent delivery to the priming line after the centrifugal pump is in full operation.

As here shown, the valve casing 6 is mounted directly on the casing of the centrifugal pump 5 and has a passage 7 registering on the one hand with the priming port 8 in the pump casing, and on the other hand with the chamber 9 to one side of the check valve 10. On the opposite side of the latter, the chamber 9 has a port 11 which opens to the suction chamber 12 to which the suction line S to the priming pump P is connected.

The stem 13 of the valve passes through port 11 and guide boss 14 on the valve cas-

ing, and is screwed at its outer end into the head 15 of a yoke 16 connected in any appropriate fashion to the core 17 of a solenoid winding 18. The latter may be conveniently supported upon a bracket arm 19 in extension of the valve casing. The packing of the guide boss 14 is obviated by a washer 20 arranged on the valve stem and pressed by the yoke head 15 against a seat 65 in the outer face of the boss 14 in the open position of the valve 10, thus sealing the guide passage through the boss 14 and preventing air leakage at this point while the priming pump is in operation. 70

The valve 10 is cupped and provided with a peripheral bearing flange 21 which makes seal with the wall of the valve chamber 9. Ports 22 preferably opened through the side wall of the valve (or through the bearing flange 21) establish communication between opposite ends of the chamber 9 through the valve. A washer 23 mounted in a seat on the opposite face of the valve head is pressed, in closed valve position, against the 80 seat 24 in the diaphragm 25 through which the port 11 is opened, and thus seals this port against flow to the priming pump when the centrifugal 5 is in operation. The combined cross-sectional area of the 85 ports 22 in the valve is less than the unobstructed cross-sectional area of the port 11 in diaphragm 25 for a reason that will be hereinafter pointed out.

While the solenoid winding 18 may be 90 energized from any suitable source, I prefer to arrange it in series with the motor M which drives the priming pump P so that while the latter is in operation the solenoid tends constantly to hold the valve open. 95 The pull of the solenoid winding upon the core 17 is in the direction of the arrow X.

The operation of the valve is readily understood. Assuming the solenoid 18 to be energized, for example by closing the circuit 100 of the priming pump motor M, the valve is shifted to the open position illustrated, and the suction of the priming pump exhausts the centrifugal pump 5 through port 8, passage 7, chamber 9, valve ports 22, diaphragm port 11, suction chamber 12 and suction line S. By reason of the suction effort exerted by the pump, and the greater area of the port 11 than the valve ports 22, there is greater depression on the suction line side 110 of the valve than on the side toward the centrifugal pump 5, and as a consequence the

valve tends to close. The solenoid 18 is sufficiently powerful, however, to prevent this. When the centrifugal pump has been fully primed and has been set in motion, it delivers 5 not only through its discharge outlet (not shown) but also through the port 8 to the the valve chamber 9. By reason of the restricted area of the ports 22 in the valve, which permit less flow therethrough than the 10 port 11 can readily accommodate, pressure is built up on the centrifugal pump side of the valve 10 and, overcoming the opposition of the solenoid 18 forces the valve to its closed position in which the washer 23 seats 15 against the diaphragm 25 and seals the port 11. Further delivery by the centrifugal pump to the priming suction line S is thus cut off and remains cut off until the centrifugal pump requires repriming and the 20 priming pump is again set in motion.

It will be understood that the priming pump is maintained in operation only until the centrifugal pump is fully under way and working properly, whereupon the priming 25 pump is halted during the run of the centrifugal pump. It is desirable from a practical standpoint, however, that the priming pump be kept in operation during the initial drive of the centrifugal pump—i. e., until it 30 picks up full speed.

As matters of structural convenience afforded by the present invention, attention may be called to the fact that the valve chamber 9 is closed by the detachable cap 35 26, so that the valve may be readily removed for inspection and repair after it has been unscrewed from the solenoid head 15. Again, a plug 27 may be arranged in the valve casing opposite the passage 7 and port 40 8 so that a clean-out tool may be inserted therethrough to remove any obstruction which may have lodged therein during the operation of the centrifugal.

The construction is simple and efficient.

45 The connection of the solenoid winding in series with the priming pump motor, renders the opening of the valve positive at the moment when the suction connection must be established, while there is no effort to open 50 the valve or to lessen its effective seal during the operation of the centrifugal pump, as would be the case were the valve stressed toward open position by springs.

Various modifications of construction will

55 readily occur to those dealing with the problem which do not depart from what I claim as my invention.

I claim—

60 1. In a priming system for centrifugal pumps, a suction line connected to the pump casing, a check valve arranged in the suction line, and electromagnetic means for holding said valve open during the priming operation.

65 2. In a priming system for centrifugal

pumps, a suction line connected to the pump casing, a check valve arranged in the suction line, and electromagnetic means for holding said valve open during the priming operation, said check valve being adapted 70 for closure by the delivery from the centrifugal pump when the latter is in operation.

3. In a priming system for centrifugal pumps, a suction line connected to the pump 75 casing, a check valve arranged in the suction line and ported to permit suction effort to be exerted therethrough, the ports in the valve having a total cross-sectional area less than the cross-sectional area of the passage 80 on the suction line side of the valve.

4. In a priming system for centrifugal pumps, a suction line connected to the pump casing, a check valve arranged in the suction line and ported to permit suction effort 85 to be exerted therethrough, the ports in the valve having a total cross-sectional area less than the cross-sectional area of the passage on the suction line side of the valve, and means for maintaining said valve open despite the pressure drop on the suction line 90 side of the valve.

5. In a priming system for centrifugal pumps, a suction line connected to the pump casing, a check valve arranged in the suction 95 line and ported to permit suction effort to be exerted therethrough, the ports in the valve having a total cross-sectional area less than the cross-sectional area of the passage on the suction line side of the valve, and means for yieldably maintaining said 100 valve open despite the pressure drop on the suction line side of the valve.

6. In a priming system for centrifugal pumps, a suction line connected to the pump 105 casing, a check valve casing arranged in the suction line, a piston check valve arranged within the casing and having passage means therethrough to permit communication between opposite sides of the valve, and means for yieldably holding said valve in open 110 position against the effort exerted in the suction line.

7. In a priming pump system, an electric motor-driven priming pump, a suction line 115 connected thereto, in combination with a check valve arranged in the suction line, and electromagnetic means energized during the drive of the pump motor for stressing said valve to open position.

8. In a priming pump system, an electric motor-driven priming pump, a centrifugal pump, a suction priming line between said pumps, a check valve arranged in said line, and means operative during the drive of 125 said motor to stress said valve to open position, but yieldable to permit the valve to close under the pressure of the delivery from the centrifugal pump.

9. In a priming system for centrifugal 130

- pumps, a suction line connected to the pump casing, a check valve casing arranged in the suction line and having a valve chamber, a suction chamber communicating therewith through a port, a check valve controlling said port, a stem on said check valve passing through the suction chamber and valve casing and guided by the latter, together with sealing means associated with the valve 5 stem and arranged exterior to the casing, together with means for simultaneously shifting the valve to open position and pressing said sealing means against the outer face of the casing to prevent leakage at the 10 valve stem guideway in the casing during the pump-priming operation.
10. In a priming system for centrifugal pumps, a suction line connected to the pump casing, a check valve casing arranged in the suction line and having a valve chamber, a suction chamber communicating therewith through a port, a check valve arranged in the valve chamber and having a stem passing 15 through said port and suction chamber 20 and casing to the exterior of the latter, to- 25
- gether with a washer on the stem side of said valve adapted to seal the said port in closed-valve position.
11. In a priming system for centrifugal pumps, a suction line connected to the pump 30 casing, a check valve casing arranged in the suction line and having a valve chamber, a suction chamber communicating therewith through a port, a check valve arranged in the valve chamber and having a stem passing 35 through said port and suction chamber 40 and casing to the exterior of the latter, a washer on the stem side of said valve adapted to seal the said port in closed-valve position, a washer mounted on the valve stem exterior to the casing, together with means for simultaneously moving the valve to port opening position, and for pressing the washer on the valve stem against the exterior of the casing to seal the latter against leakage 45 at the valve stem passage-way therethrough during the priming operation.

In testimony whereof I have signed my name to this specification.

OTTO HAENTJENS.
